Inventor.

W. E. Gibbons.

UNITED STATES PATENT OFFICE.

WILLIAM EDWARD GIBBON, OF COLCHESTER, ENGLAND.

EXPLOSIVE-ENGINE.

SPECIFICATION forming part of Letters Patent No. 585,484, dated June 29, 1897.

Application filed October 24, 1896. Serial No. 609,946. (No model.)

To all whom it may concern:

Be it known that I, WILLIAM EDWARD GIBBON, a subject of the Queen of Great Britain, residing at Colchester, England, have invented new and useful Improvements in Explosion-Engines, of which the following is a specification.

My invention chiefly relates to explosion-engines of the kind described in the specification of my former United States Patent No. 547,606, dated October 8, 1895, and comprises improvements for enabling the piston to receive an impulse at every revolution, in the means for operating the oil-pump, in the construction of the vaporizer, and in the arrangement for causing the circulation of water through the cooling-jackets; but my improvements are partly applicable to engines of the closed crank-pit type, or of the kind wherein the front of the cylinder is closed to form a chamber.

According to my invention I make use of a differential piston and cylinder—that is to say, a piston having a larger area at one side than at the other and a cylinder bored out to different diameters at the two ends to receive the said piston. I arrange the larger end of the cylinder in connection with a closed chamber, which may be the crank-pit in which the crank works or a chamber on the cylinder, so that at each outstroke of the piston under the force of an explosion the air in the said chamber will be compressed and forced around into the combustion-chamber to drive out the products of combustion of the previous charge through a port in the side of the cylinder which is uncovered when the piston is at the limit of its outstroke and to mingle with the hydrocarbon vapor for the formation of an explosive charge.

The oil-pump is operated by a groove in the periphery of the crank-disk acting against a lever in connection with the oil-pump, and the shield around the vaporizer described in my former specification is formed in one piece with the combustion-chamber.

The circulation of the water through the cooling-jackets is effected by the use of a pulsometer operated by the alternate compression and rarefaction of the air contained in a part of the space at the back of the large end

of the piston in the large end of the differential cylinder.

To enable my invention to be fully understood, I will describe the same by reference to the accompanying drawings, in which—

Figure 1 is a longitudinal section of an engine embodying my improvements, and Fig. 2 is an edge view of part of the crank-disk.

a is the engine-cylinder, which is of larger diameter at one end than at the other, and *b* is the trunk-piston working therein, the main part of the trunk being turned to fit the part of the cylinder of small diameter, while the end *b'* of the said piston of larger diameter fits in the part of the cylinder of larger diameter, so that a space *c* is formed behind the said enlarged part *b'* of the piston.

d is the inclosed crank pit or chamber, communicating with the large end of the cylinder *a*, the said chamber having on its exterior the lugs or brackets *e e* for supporting the engine upon a suitable bed-plate.

f is the combustion-chamber, *g* the vaporizer and igniter, and *h* the shield surrounding the said vaporizer, the construction and arrangement of these parts being substantially the same as described in my said former specification except that the shield *h*, instead of being independent of the combustion-chamber, is formed in one piece therewith, as will be clearly understood by reference to the drawings.

i is a passage formed around the large part of the cylinder *a* and communicating with the interior of the crank-chamber through the passage *i'*, and *j* is a pipe which establishes communication between the passage *i* and a jacket *i''*, surrounding the combustion-chamber, the said jacket in its turn communicating with the interior of the combustion-chamber through an opening *i'''*. An inwardly-opening valve *k* is arranged in connection with the opening *i'''* to prevent the gases in the combustion-chamber from being forced back into the jacket *i''* and also to regulate the ingoing of the compressed air.

l is a valve which operates in conjunction with a series of openings formed in the wall of the crank-chamber, the said valve being held against its seat by a spring *l'*, which will yield under atmospheric pressure.

m is the port through which the products of combustion escape when the piston is at the extremity of its outstroke.

- The operation of the apparatus as thus far described is as follows: Assume the piston to be at the end of the instroke and an explosive charge in the combustion-chamber to be ignited. As now the piston moves through its outstroke under the force of the explosion 5 the air in the crank-chamber *d* is compressed by the piston. The compression, however, is not sufficient to force the valve *k* from its seat, owing to the greater pressure which exists in the combustion-chamber. When, however, 10 the piston has moved so far on its outstroke that the port *m* is uncovered, the pressure of the air contained in the crank-chamber is sufficient to open the valve *k* against the pressure of its spring, so that the air passes the said valve and drives out the whole or part of the products of combustion from the combustion-chamber and the cylinder through the exhaust-port *m*. At the same time gas is being formed in the vaporizer, 15 which gas, issuing out at the top of the shield *h*, mingles with the air and forms a combustible charge. When on the instroke, under the momentum of the fly-wheel or crank-disk, the exhaust-port *m* is again covered, the combustible charge in the cylinder is compressed and forced into the igniter *g* and fired. At the same time the air in the crank-chamber is rarefied, so that the valve *l* opens under the atmospheric pressure and allows air to 20 enter the crank-chamber ready for compression on the next outstroke of the piston. As the pressure of the spring *l'* would prevent the complete refilling of the crank-chamber with air at atmospheric pressure I form in the walls of the cylinder *a* a series of openings *n*, which when the piston has, or nearly, completed its instroke are uncovered to place the interior of the large part of the cylinder and the crank-chamber in direct communication 25 with the atmosphere. This arrangement insures a full charge of air being taken into the crank-chamber for compression during the outstroke of the piston. It will thus be seen that at each instroke of the piston the crank-chamber is filled with air, which on the next outstroke of the piston is compressed ready, when the outstroke is completed, for forcing out the products of combustion of the previous charge and for again charging the cylinder with fresh air and gas for the next explosive charge.
- o* is the oil-pump, the plunger *p* of which is operated by a lever *q*, working in a recess in the plunger and fixed to one end of a shaft 30 *r*, the other end of which carries a lever *s*, provided at its free end with a roller *t*, running in a groove *t'* in the periphery of the crank-disk *t*, the said groove being formed

in a manner, which will be readily understood by reference to Fig. 2, so as to impart a slight oscillation to the lever *s* at each rotation of the crank-disk.

u is the valve, arranged in the manner described in my former specification in conjunction with the vaporizer for admitting the oil 50 under the action of the pump *o*.

v is a pulsometer which I advantageously employ for causing a circulation of water through the water-jacket, *v'* being the suction-pipe, *v*² the suction-valve, *v*³ the delivery-valve, *v*⁴ the delivery-pipe, which is connected to the cylinder water-jacket, and *v*⁵ an air-chamber. The pulsations for working the pulsometer are obtained by connecting the space *c* behind the enlargement *b'* of the piston with the chamber *w* of the pulsometer by a pipe *x*.

When during the instroke of the piston the openings *n n* to the space *c* are closed by the large end *b'* of the piston, the small quantity 85 of air imprisoned in the space *c* is compressed to force the water in the chamber *w* and pipe *x* of the pulsometer to pass the delivery-valve *v*³ and when on the outstroke of the piston the air in the said space *c* is slightly rarefied before the openings *n n* are uncovered the suction-valve is thereby lifted to admit water into the chamber *w* and pipe *x*, which is forced out under the next compression, and so on.

Having now particularly described and ascertained the nature of my said invention and in what manner the same is to be performed, I declare that what I claim is—

1. In an explosion-engine the combination of a differential piston and cylinder, a closed crank-chamber, a valve for admitting air into the said chamber, an opening or openings from the outer air through the cylinder into the chamber uncovered by the piston when at about the end of its instroke, and a passage 100 for conducting the air compressed in the chamber into the combustion-chamber, substantially as described.

2. In an explosion-engine having a differential piston and cylinder, a pulsometer connected with the space *c* between the back of the larger end of the said piston and the cylinder, combined with a water-jacket, connecting-pipes, and the perforated cylinder-wall, substantially as described.

3. In an explosion-engine having a crank-disk arranged in a closed chamber and having a groove formed in the periphery of said disk, the combination therewith of an oil-pump, and means substantially as described 115 for operating the same.

WILLIAM EDWARD GIBBON.
